UNITED STATES PATENT OFFICE.

CHARLES MILLER, OF NEW YORK, N. Y.

ROTARY ENGINE.

1,174,431.

Specification of Letters Patent.

Patented Mar. 7, 1916.

Application filed July 14, 1911, Serial No. 638,436. Renewed July 2, 1915. Serial No. 37,781.

To all whom it may concern:

Be it known that I, CHARLES MILLER, a citizen of the United States, residing in the city, county, and State of New York, have 5 invented a new and useful Improvement in Rotary Engines, of which the following is a specification.

My invention relates to the type of rotary engine in which one or more pistons, constituting a piston system, are driven continuously in one direction or the other about a central axis and in an approximate endless piston chamber to which said pistons are fitted, the actuating medium being any suitable gas such as steam, air, gasoline, vapor, etc., admitted to the chamber under pressure and at suitable times.

In Patents Nos. 924,173 dated June 8, 1909, 931,785 dated August 24, 1909, and 20 in my pending application 531,881 filed December 7, 1909, I have shown and described improved engines of the general type herein referred to.

My present invention relates particularly 25 to an engine of the above referred to type in which a central piston system is flanked on each of two sides by an abutment with which the piston system coöperates, and is directed especially to the shape of the piston 30 and to certain details of piston and valve construction, means for packing the several shafts against steam leakage, means for packing the pistons against steam leakage, means for packing the abutments against 35 steam leakage where they intersect the piston chamber, and means for opposing a counter pressure preferably that of live steam, upon the inside of the abutments to balance the pressure upon said abutments 40 due to the steam in the piston chamber, thereby substantially nullifying the effect of steam pressure upon the abutment journals.

My invention also includes a novel arrangement of steam admission ports and 45 means for their control whereby the engine may be more readily and quickly started under load.

My present invention is further directed 50 to an arrangement of the valves and steam passages with relation to the general engine structure such that the incoming steam may be quickly effective upon the pistons and "wire drawing" in the passages be prevented.

55 The object of my invention is to produce a rotary engine of high efficiency in which

steam leakage is effectively guarded against, mechanical friction is avoided to a great extent, and piston clearance is made small.

A further object of my invention is to 50 provide a construction in which the moving parts are balanced so as to permit of a high speed of operation.

A further object of my invention is to 55 provide a valve capable of easy adjustment in case of wear.

Other objects will appear as the specification proceeds.

Referring to the drawings, which are hereby made a part of the specification, Fig. 1 is a front elevation of a preferred form of my improved engine; Fig. 2 is a plan view of the same, some of the parts being omitted for the sake of clearness; Fig. 3 is a horizontal section taken from above, substantially along the line 3—3 of Fig. 1; Fig. 4 is an elevation, similar to that of Fig. 1, but with that portion of the engine casing forward of the line 4—4 (Figs. 2 and 3) removed so as to expose the interior 80 structure and with the governor and some of the piping connected thereto omitted; Fig. 5 is a sectional elevation taken along the line 5—5 of Fig. 4; Fig. 6 is a sectional view, enlarged, showing the means employed, at the intersection of the abutments with the piston chamber, for introducing live steam on the inner side of the abutments for the purpose of counteracting the component of the working steam pressure 90 on the outer side of the same; Fig. 7 is a transverse section, taken along the line 7—7 of Fig. 6; Fig. 8 is a section, similarly enlarged, showing details of the valve construction and adjustment as also the means used for packing an abutment against steam 95 leakage where it intersects the piston chamber; Fig. 9 is a section taken along the line 9—9 of Fig. 8; Fig. 10 is a section taken along the line 10—10 of Fig. 8; Fig. 11 is 100 a central vertical section, similarly enlarged, taken along the line 11—11 of Fig. 4; Fig. 12 is a similarly enlarged elevation of the assembled piston, and Fig. 13 is a diametral section taken along the line 13—13 of Fig. 105 12; Fig. 14 is a similarly enlarged elevation showing the assembled valve; Fig. 15 is a diametral section of the valve taken along the line 15—15 of Fig. 14; Fig. 16 is a side elevation of the valve of Fig. 14; Fig. 17 is 110 an edge elevation of one of the abutments drawn to the same scale as Figs. 1 to 4; and

Figs. 18 and 19 are respectively plan and side elevation (drawn to the same scale as Fig. 17) of the valve controlling device used when starting my improved engine under load.

5 Essentially my improved engine comprises a central piston system 1, having two opposite identical pistons 2, 2, united by a thin core 3, adapted to coöperate with two 10 identical abutments 4, 4', symmetrically arranged one on each side of the piston system. A suitable casing 5, consisting of closely similar front and rear portions 6, 6', and provided with a steam chamber, a 15 piston chamber, valves, suitable steam passages, and incidental structural and operative features, incloses the piston system and the abutments and is supported upon a suitable base 7.

20 For convenience of manufacture and assembly the casing 5 is made in a number of sections comprising front and rear cylinders 8, 8', in which is formed the steam chamber 8², major part of the piston chamber 9; end 25 section 10 comprising segments of rings embracing a considerable part of each abutment 4, 4', and bolted at 11 to the cylinder heads; front and rear abutment heads 12, 12' bolted to the end sections 30 10 and to blocks 18 described later; packing boxes 13 closing the abutment heads and the rear cylinder head centrally; and a main packing box 14 closing the central opening of the front cylinder head and carrying the outboard bearing 15 for the main 35 shaft 16 upon which is keyed the piston system. The packing boxes 13 for the two front abutment heads also constitute journal boxes for the shafts 17 to which are 40 keyed the two abutments.

45 For reasons to be later set forth those portions of the piston chamber 9 which fall within the periphery of the two abutment systems 4, 4', are formed in separate blocks 45 18 (Figs. 3, 6 and 7); these blocks are substantially circular segments and each is made in two halves which are respectively bolted at 19 to the front and rear cylinder heads.

50 The abutments (Figs. 4 and 17) are of the general type shown in my Patent 924,173 previously referred to and, in an improved form, in my pending application Serial No. 531,881. Each is a structure 55 comprising two identical and diametrically opposite thin tubular segments or heads 20 having ends and sides respectively parallel and perpendicular to shaft 17, said segments being centrally united as also affixed to said 60 shaft by a thin core 21. Opposite sides of opposite segments are united by narrow ring sections 22 at top and bottom, these rings usually being continuing portions of the segments themselves and hence integrally a 65 part thereof. Each pair of segments is

adapted to move in an annular abutment slot 23 which is formed in the casing 1 and intersects the piston chamber 9. This slot is axially longer than the diameter of the piston chamber, thus extending beyond said 70 chamber on each side.

The cylinder heads 8, 8' are hollow or cupshaped, are faced outside the piston chamber 9 so as to be bolted together, and spaced apart inside said piston chamber so 75 to hug the face of the piston core 3 just outside the shoulder 24 (Fig. 12), the heads being bored out cylindrically for this purpose and to slidably engage the cylindrical valves 25 which are fastened to the two 80 faces of the piston system by bolts 26 (Fig. 14) and revolve with it. Each valve comprises an outer tubular section in which are opposite inlet ports 27, an inner tubular section joined to the hub of the piston system by bolts 28 (Figs. 8, 10 and 11), and a web connecting said two sections through which web pass the aforesaid bolts 26. To allow of adjustment of these valves for wear each is preferably made in three segments which are individually radially adjustable by means of the bolts 26 and 28, the web being slotted for the purpose where bolts 26 pass through; and to avoid steam leakage at the junctions of the valve segments a spring pressed closure plate 29 is fitted to each of said junctions (Figs. 14 and 15) so as to maintain the same permanently closed. This closure plate has a curved peripheral portion which is conformed to the inner surface of the outer tubular section of the valve and a flange portion 30 dovetailed into the edge of said outer tubular section whereby the closure plate is maintained in position.

105 To coöperate with the valve ports 27 two sets of diametrically opposite main inlet ports 31 are formed in each cylinder head just above the intersection of the abutment 4 with the piston chamber 9 on the left of the engine (Fig. 1) and just below the corresponding intersection on the right hand side. Steam is admitted by a main inlet pipe 32 directly to the steam chamber 8² of the rear cylinder head. Exhaust ports 33 corresponding to the inlet ports 31 are located diametrically opposite one another (Fig. 4) at the lower intersection of abutment and piston chamber to the left of the engine and at the upper intersection to the right of the engine; they communicate with the two members 34 of a bifurcated exhaust pipe 35. Holes 35' bored through the piston core 3 connect the two steam chambers 8² of the front and rear cylinder heads. Shaft 16 110 carrying the piston system 1 and shafts 17 carrying the abutments 4, 4' are provided, on one side of the engine, with gear wheels 36 of equal diameter meshing with one another and thus compelling the shafts to ro- 115 120 125 130

tate with the same angular velocity; these pulleys may be inclosed in a protecting casting 37. By providing any one of the three shafts (one of the shafts 17 in the drawing) preferably the main shaft 16, with a smooth pulley power may be taken from the engine. A governor 38 of conventional type and driven from any one of the shafts acts directly upon the steam supply to control the same in the usual way according to the speed.

The operation of my improved engine is as follows: The moving parts being as indicated in Fig. 4, steam having been admitted to the main inlet pipe 32 instantly fills the steam chamber 8 of the front cylinder head and, through the holes 30, the corresponding steam chamber of the rear cylinder head and from both of said steam chambers passes through the inlet ports 27 of both valves 25 into and through the main inlet ports 31 in the walls of the cylinder heads into the piston chamber 9 between the pistons 2 and the abutment heads 20. As shown in Fig. 4 the valve ports 27 and the inlet ports 31 have just begun to register or uncover one another; of course, if these valves are entirely out of register the engine will require to be "turned over" by hand so as to bring said valves into registry before the engine can be started. The pistons will thus be driven in the direction of the arrow, the valves 25 being carried with the pistons so as to shut off the inlet ports 31 after rotation through an angle the magnitude of which will depend upon the dimensions of the ports 27 and 31. So soon as the steam is thus cut off, each piston, which will have rotated through the same angle, will continue to rotate under the expansion of the steam now in the piston chamber until it has reached and left behind some portion of the exhaust port 33 when the steam will begin to exhaust through said port and the exhaust pipes 34 and 35. By reason of the meshed gear wheels 36 the abutments 4, 4' rotate with the piston system 1, so that as each piston 2 passes the exhaust port 33 it enters the opening between the abutment heads 20 passing out of said opening just before it traverses the inlet ports 31.

To insure steam tight connection between each piston 2 and the steam chamber 9, spring rings 38 are peripherally attached to said pistons, as is practised in reciprocating engines. To prevent steam being lost from the piston chamber 9 past the abutment head 20, I employ an abutment packing ring 39 (Fig. 8) let into the cylinder head so as to surround said piston chamber; this ring is conformed to the curve of the abutment head and kept pressed against said head by coiled springs 40. This ring is positioned, of course, before the blocks 18 are

attached to the cylinder heads. Since the opening between the abutment heads 20 does not extend into the abutment slots 23 and since these heads are connected within these slots by bands continuous and integral with said heads the packing rings will always ride smoothly upon said bands. 70

Steam being simultaneously admitted to diametrically opposite portions of the piston chamber, the resultant lateral pressure upon the main shaft 16 is always perfectly balanced so that this shaft should run with but slight journal friction. There is, however, no such normal balancing for the pressure effective upon the outside of abutment heads 20 so that normally not only would there be excessive journal friction between the shafts 17 and their bearings, but the abutment heads themselves, being of relatively thin material, would tend to bend as they pass through the piston chamber 9 behind the advancing piston and bind against the walls of the abutment slot 23. To compensate for this unbalanced pressure upon the abutment heads, I arrange a number of pressure compensators 41 (Figs. 4, 6 and 7) in each of the blocks 18 along and adjacent interiorly to the edges of the abutment slots 23 where said slots intersect the piston chamber 9. Each of these pressure compensators comprises a tubular plug 41' screwed into block 18 so as to have an outer cup shaped end spaced from the abutment slot and an annular space around this cup shaped end in which is a small packing ring 42 having a face conformed to the curve of the abutment head and kept outwardly pressed against said head by a coiled spring 43. The opening 44 through the center of plug 41 connects the space at the outer end of the plug with chamber 45 in block 18 and into this chamber live steam is brought direct from the main inlet pipe 32 by means of auxiliary pipes 46'. Each pressure compensator 41, therefore, exerts an outward pressure upon the abutment head 20 opposing the inward pressure due to the working steam in the piston chamber 9 and the magnitude of this pressure, is, of course, proportional to the area of the abutment head surface inclosed by the packing ring 42. By causing the sum of the surface areas inclosed within the several packing rings to be equal to half of the area which is exposed to the working steam pressure in the piston chamber, *i. e.*, to half of the abutment head area cut off by the piston chamber the average inward pressure due to the working steam in the piston chamber will be perfectly balanced. 115

Live steam for the pressure compensators need not, of course, be taken direct from the main steam pipe, but connection may be made to any convenient point. Or the pressure compensators may be connected with 130

the piston chamber at or near the inlet ports 31, so that the pressure per unit of area due to the compensators will rise and fall exactly as does the working pressure per unit of area upon the outer periphery of the abutment head; in this case the sum of the compensator areas should equal the abutment head area cut off by the piston chamber.

10 After a piston has passed an exhaust port 33 and as it is passing to a corresponding position on the other side of the horizontal center line of the engine, consideration will show that the volume between the piston 15 and the abutment head just in advance of said piston is constantly decreasing so that any steam or air contained therein will be compressed. This, of course, will operate like any other back pressure and tend to 20 lessen the speed of the engine and to lower its efficiency. To prevent this result I provide an auxiliary exhaust just in advance of the main exhaust in the form of elongated openings 46 (Fig. 6) in the sides of that 25 portion of piston chamber 9 which is formed in block 18. These openings begin just in advance of the exhaust ports 33, widening as they go, and terminate near the horizontal center line of the engine; they open 30 into the exhaust pipes 34.

In order to lessen the clearance at the rear end of each piston between said piston and the abutment heads 20 and thereby increase the efficiency of my engine, I shape 35 said piston end to curve outwardly and laterally so that as the piston passes into the open space between the abutment heads every part of said end will just escape touching the adjacent end of the abutment head.

40 Mathematically the shape of this piston end is such that its intersection with each and every plane passing through it perpendicular to the axis of rotation of the piston system will be an epicycloid regardless of the 45 relative speeds of the piston system and of the abutments.

To prevent steam leaking from the interior of the engine along the shafts 16 and 17, I employ packing rings 46 (Figs. 3 and 50 11) set in recesses formed upon the inner faces of the packing boxes 13 and 14 and pressed outwardly against the hubs of the abutments and of the piston system by coiled springs 47. The abutting faces of 55 said hubs and of the corresponding faces of the packing rings and packing boxes 12 and 14 must, of course, be accurately machined and surfaced.

Oil cups 48 are placed at the top of steam 60 pipes 46 and by their means oil is introduced into the engine between the compensator packing rings 42 and the abutment heads.

In describing the operation of my improved engine, I have stated that, if the 65 valve ports 27 and the inlet ports 31 are

out of registry, the engine will require to be turned over by hand in order to start it. This procedure may be avoided by providing additional inlet ports, similar to the inlet port 31, between the steam chambers 8² and 70 the piston chamber 9 and in advance of port 31, these additional ports being positioned to register successively with the valve port 27 as the valve rotates and provision being made for closing these extra ports as soon 75 as the engine is well started. In the drawings (Figs. 4 and 11) I have shown but one additional port in advance of each port 31 others being omitted to avoid confusion; in practice as many extra ports may be used 80 as is thought desirable.

To open and close the extra ports 49 at will I employ a valve closure comprising two tubular segments 50 (Figs. 18 and 19) each of which is snugly fitted in an annular recessed portion 51 of the rear cylinder head 8¹ lying just outside of the valve 25, so as to have close contact with the inner periphery of the cylinder head end with the outer periphery of the valve. These segments are 90 united to arms 52 which join a central ring 53 rotatably mounted upon the packing box 13. Teeth upon the outer periphery of ring 53 mesh with a pinion 54 fixed to a spindle 55 carried upon the same packing box 13; 95 this spindle has an outer squared end adapted to be engaged by a key so as to be rotated. In this way the extra ports 49 will be closed off or opened by the segments 50. This provision of the extra ports will be 100 found particularly useful in starting the engine under load since each port enables the piston to be acted upon by the full pressure of the live steam instead of requiring that the piston move from the main inlet to the exhaust port under the expansion of a 105 single initial charge of steam.

Instead of making my valve in sections which are radially adjustable to take up wear, I may if I prefer place a spring 110 pressed packing ring about the steam ports so as to bear against the valve. The construction of this ring and its mode of attachment to the casing may be similar to that used for the abutment packing ring previously described.

I claim:

1. In a rotary engine having a casing provided with an annular piston chamber and a piston adapted to rotate in said chamber, 120 the combination of an abutment head adapted to periodically intersect said piston chamber, said head comprising opposite segments united by top and bottom ring sections and packing means surrounding the piston chamber and adapted to press against said ring sections to prevent steam leakage.

2. In a rotary engine having a casing provided with an annular piston chamber and a piston adapted to rotate in said chamber, 125

the combination of an abutment head adapted to periodically intersect said piston chamber, said head comprising opposite segments united by top and bottom ring sections, a packing ring surrounding the piston chamber adjacent to said abutment and pressing against said ring sections, and springs pressing against said rings.

3. In a rotary engine the combination of a casing provided with an annular piston chamber and opposite steam chambers, a piston system provided with a core which constitutes a wall between the said steam chambers and having pistons adapted to rotate in said piston chamber, and an abutment head adapted to coöperate with said pistons, said core having holes therethrough for the passage of steam from one steam chamber to the other.

20 4. In a rotary engine the combination of a casing provided with an annular piston chamber and opposite steam chambers having walls concentric with said piston chamber, a piston system provided with a core 25 which constitutes a wall between said steam chambers and having pistons adapted to rotate in said piston chamber, an abutment head adapted to coöperate with said pistons, ports in the walls of said steam chambers communicating with the piston chambers and a valve fixed to the core of said piston system and adapted to control said ports.

5. In a rotary engine having an annular piston chamber, a steam chamber provided 35 with walls concentric with said piston chamber and having ports communicating with said piston chamber, and a rotary valve adapted to engage the walls of said steam chamber and control the ports, said valve

being adjustable as to its periphery to compensate for wear.

6. In a rotary engine a cylindrically bored steam chamber provided with ports, and a rotary valve adapted to engage the walls of said chamber and control the ports, said valve being in sections and adjustable as to its periphery to compensate for wear.

7. In a rotary engine provided with an annular piston chamber, a piston adapted to rotate in said chamber, an abutment adapted to intersect said chamber and coöperate with said piston, and means for admitting working steam between said piston and said abutment; means comprising passages surrounded by packing rings bearing upon the abutments for applying pressure to the abutment in opposition to the pressure of the working steam.

8. In a rotary engine having an annular piston chamber, a piston adapted to rotate therein, and a steam chamber provided with walls concentric with said piston chamber, a plurality of inlet ports connecting said steam chamber with said piston chamber, a rotary valve adapted to engage the walls of said steam chamber so as to open and close all of said ports successively as the piston rotates and means independent of the piston and the valve also adapted to open and close some but not all of said ports.

In testimony whereof I have hereunto set my hand in the presence of two subscribing witnesses.

CHARLES MILLER.
